UNITED STATES PATENT OFFICE.

EDWARD FIELD GOLTRA, OF ST. LOUIS, MISSOURI.

DESIGN FOR A CAR-TRUCK SIDE FRAME.

SPECIFICATION forming part of Design No. 26,114, dated September 29, 1896.

Application filed August 20, 1896. Serial No. 603,419. Term of patent 14 years.

To all whom it may concern:

Be it known that I, EDWARD FIELD GOLTRA, a citizen of the United States, residing at St. Louis, State of Missouri, have invented a certain new and useful Design for Car-Truck Side Frames; and I do hereby declare the following to be a full, clear, and exact description of the invention, such as will enable others skilled in the art to which it appertains to make and use the same.

The accompanying drawing illustrates in side elevation a car-truck side frame embodying my design.

Referring to the drawing, *a* denotes the top bar; *b*, the bottom bar; *c*, the axle-box pedestal and top spring-seat; *d*, the bolster-pedestal and bottom spring-seat, and *e* the connecting truss-bar.

The distinguishing characteristic of the design is that the bolster-pedestal and bottom spring-seat are integral and of general U

shape, and the axle-box pedestals and top spring-seats are also integral and of general inverted-U shape in a construction wherein the truss-bar is substantially horizontal at its ends and middle portion, with inclined intermediate portions crossing diagonally the spaces between the axle-box pedestals at the ends and the bolster-pedestal at the center of the frame, and wherein the top bar *a* arches slightly upwardly at its middle portion.

Having thus described my design, what I claim is—

The design for a car-truck side frame, substantially as herein described and shown. 35

In testimony whereof I affix my signature in presence of two witnesses.

EDWARD FIELD GOLTRA.
